Assistant Examiner — Benjamin L. Gray

(57) **CLAIM**

The ornamental design for a set of car interior door handle covers, as shown and described.

DESCRIPTION

FIG. 1 is a perspective view of a first car interior door handle cover of a set of car interior door handle covers showing my new design shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second car interior door handle cover of the set of car interior door handle covers shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the set of car interior door handle covers where the set of car interior door handle covers is in a configuration of use.

The broken lines in FIG. 17 depict environment and form no part of the claimed design.

1 Claim, 17 Drawing Sheets
